UNITED STATES PATENT OFFICE.

JOHN J. HOPPES, OF SPRINGFIELD, OHIO.

FEED-WATER HEATER.

SPECIFICATION forming part of Letters Patent No. 273,084, dated February 27, 1883.

Application filed June 6, 1882. (No model.)

To all whom it may concern:

Be it known that I, JOHN J. HOPPES, of Springfield, in the county of Clarke and State of Ohio, have invented a new and useful Improvement in Feed-Water Heaters, of which the following is a full, clear, and exact description.

My improvements relate to apparatus for heating and filtering the feed-water of boilers and extracting the lime and other foreign matters therefrom.

The invention consists in certain essential features of construction hereinafter described and claimed.

Reference is to be had to the accompanying drawings, forming a part of this specification, in which similar letters of reference indicate corresponding parts in all the figures.

Figure 1 is a vertical section of my improved feed-water heater. Fig. 2 is a transverse section on line xx of Fig. 1. Fig. 3 is a cross-section on line yy of Fig. 1. Fig. 4 is a sectional elevation of the lower portion of the apparatus at right angles to Fig. 1, and showing the discharge-pipe and filter; and Fig. 5 is a detail view.

A is a hollow cylinder of metal, of suitable diameter and length, and fitted with cast-iron heads aa .

At the center of the cylinder A is a shaft, b , that is stepped at its lower end in a cross-brace, c , and supported at its upper end by a cross-brace, c' . This shaft is provided at its lower end with a beveled pinion gearing into a similar pinion upon the end of a shaft, a , that extends to the outside through a stuffing-box in the side of the cylinder A, and this shaft d is provided with a crank-handle for its rotation to give rotation to the shaft b , and in apparatus of large size the cross-shaft may be provided with a pulley for receiving a belt, so that the shaft b may be rotated by power.

Fixed upon the shaft b are the bowl-shaped receivers B, of concavo-convex form, their diameter at their upper edges being somewhat smaller than the interior of the cylinder A, so as to give free space for the escape of the water.

D D are the scrapers, the same being narrow blades of metal shaped to the form of the bowls B on both their lower and upper edges. These scrapers are connected at their

outer ends to a vertical rod or shaft, e , which extends through the cylinder A at one side. They are also connected by braces f at their outer ends to a second shaft, g , that extends through the cylinder at one side of and at a suitable distance from the rod e , the object of this brace and second shaft being to prevent the scrapers from turning. The rod e is sustained at intervals by eyes h , attached to the side of the cylinder A, and the two rods are connected at both their upper and lower ends by curved bars i . The lower connecting-bar, i , is slotted to receive the end of a jointed link, K, by which the bar is connected to an arm on a shaft, l , which shaft is supported in a horizontal position and extends through a stuffing-box in the side of the cylinder A, its outer end being provided with a lever, m , by which the shaft can be turned in either direction, and the two rods e g , with the scrapers, thus raised and lowered.

The feed-water-supply pipe n enters at the upper part of the cylinder A in position for discharging into the upper bowl or receiver, B. Near the bottom of the cylinder is a pipe, o , for drawing water from the lower part of the cylinder, which may be done by means of a pump. Over the opening into the discharge-pipe o , and within the cylinder, is fixed a filtering-box, p , formed with perforated side plates, between which is contained any suitable filtering medium. The space beneath the lower bowl B and the bottom of the cylinder A forms a reservoir for receiving the heated water which is to be drawn from it by the pipe o .

At one side of the cylinder A, and near the bottom, is an inlet-opening, q , provided with a coupling for the connection of the exhaust-steam pipe, and this opening is covered at the side by a curved or concave plate, r , this plate being open at its side to allow exit of the steam.

In the bottom head of the cylinder A is a waste-pipe, s , provided with a valve, t , that is fitted for being opened by hand when the apparatus is to be cleaned. The cylinder is also provided with a door, u , near its lower end, for giving access to the interior.

In the operation of the apparatus the feed-water supplied by the pipe n fills the upper bowl or receiver B, and, flowing over the upper edges of the same, falls into the second

bowl, and so on until they are all filled and the water passes to the receiving-space at the bottom of the cylinder. The bowls are of such form that the water flowing over their edges 5 clings to their under sides until near the middle or center of the bowl. The water is thus discharged directly into the bowl beneath, and being spread over the surface is more readily heated. The exhaust-steam, entering at *q*, fills 10 the interior of the cylinder and retains the bowls in a heated condition. In this manner the water may be heated to any extent desired. The lime and other impurities contained in the water will settle, and the receivers *B* will 15 retain such impurities.

To clean the apparatus the waste-valve *t* is to be opened, the shaft *d* given a few rapid turns, and the shaft *b*, with the bowls, being thus 20 rotated, the water and loose material will be thrown out from the bowls by centrifugal action. During this operation the scrapers *D* are to be raised to their highest position, after 25 which by turning the lever *m*, the scrapers are to be brought down within the bowls, which being set in rotation, the material adhering to the inner surface of the bowl is scraped off. The lever will be then turned in 30 the opposite direction to raise the scrapers into contact with the under sides of the bowls in order to scrape the adhering material therefrom. Water is to be supplied at the top to fill the bowls, and they are again emptied by turning the shaft *d*, and this is to be done re-

peatedly until only clear water comes from the waste-pipe. The apparatus is thus cleaned 35 without removing any of its parts, and the operation can be very quickly performed. The door *u* is to be removed when it is necessary to renew the filter *p*. The water being heated as it runs over the bowls *B* and flows 40 on or clings to their under sides by direct contact with the ascending current of heat or steam, there is no loss of heat, as would occur from heating the water through a sheet of metal and the lime and impurities constantly 45 being deposited thereon.

Having thus described my invention, I claim as new and desire to secure by Letters Patent—

1. In feed-water heaters, the combination, with cylinder *A*, of the receivers *B*, sustained 50 upon the shaft *b*, that is fitted for rotation within the cylindrical casing *A*, substantially as described.

2. In feed-water heaters, the adjustable scrapers *D*, in combination with the bowl-shaped receivers *B*, substantially as described. 55

3. In feed-water heaters, the combination of the scrapers *D*, the rods *e g*, and the shaft *l*, provided with a handle for its movement to raise and lower the rods and scrapers, sub- 60 stantially as shown and described.

JOHN J. HOPPES.
